UNITED STATES PATENT OFFICE.

BENJAMIN F. KORTEN, OF PORTLAND, OREGON.

SANITARY CUSPIDOR.

1,231,385.

Specification of Letters Patent. Patented June 26, 1917.

Application filed March 6, 1917. Serial No. 152,712.

To all whom it may concern:

Be it known that I, BENJAMIN F. KORTEN, a citizen of the United States, residing at Portland, in the county of Multnomah and State of Oregon, have invented certain new and useful Improvements in Sanitary Cuspidors, of which the following is a specification.

The basic object of this invention is to provide a cuspidor which shall be sanitary, ornamental in appearance, and susceptible of manufacture at a low cost.

The adhesion of sanguinary saliva to the interior surface of a cuspidor-bowl cannot be overcome by intermittent flushing of the same, and, when such flushing is depended upon to remove the saliva, a certain portion of the same, with its disease-breeding germs will accumulate and, ultimately, dry in the cuspidor, rendering the same unhealthy, as well as unsightly. This difficulty I overcome by providing means for continuously flushing the cuspidor, or continuously flooding the same, so that the saliva, etc., will not impinge the same and adhere thereto.

Another object is to provide an auxiliary bowl, associated with the cuspidor-support, for the reception of cigar-stumps, match-stems, etc., and provided with means for conveniently admitting water thereto and for removing dirty water therefrom.

Another object is to provide a novel form of woven-wire baskets, adapted to be disposed in said auxiliary bowl, which may be easily removed, and which facilitate cleaning of the bowl.

With these objects in view, and others appearing as the specification proceeds, the invention resides in the novel construction, combination and arrangement of parts of a cuspidor, as will be hereinafter fully described in the specification, summed up in the claims, and illustrated in the drawing.

The accompanying drawings, in which like reference-characters denote corresponding parts throughout the several views, disclose one form of embodiment of my invention capable of carrying out the underlying principles thereof. The several figures of the drawing may be briefly described as follows:

Figure 1 is a perspective view of a cuspidor embodying my inventive improvements;

Fig. 2 is a central, vertical, sectional view through the cuspidor; and

Fig. 3 is a horizontal section on the line

3—3, Fig. 2, looking in the direction of the arrows.

Referring, now, in detail to the drawing:

1 designates the base of the cuspidor, which, as shown, may be an inverted cup-shaped member, adapted to rest upon the ground or floor.

An open-top reservoir 2 may be formed integral with, or separate from, the base 1, being preferably united thereto by a neck 3. 65 This reservoir is adapted for the reception of discarded cigar- or cigarette-stumps, match-stems, etc.

Disposed concentrically within and projecting through the reservoir 2 and base 1 70 is a vertical trunk or tube 4, carrying, at its top, a sputum-bowl 5, which, as shown, is preferably formed with double, spaced walls, the inner wall 5' being formed, at its bottom, with exit openings 6, discharging into a 75 vertical waste-pipe disposed concentrically within the tube 4, and connecting with a sewer, or the like (not shown). Preferably the base 1, the reservoir 2, the bowl 5, and the tube 4 are made an integral structure, as 80 by welding the parts together.

Extending longitudinally within the tube 4 is a pipe 8, connecting with a water-main (not shown), or other source of water under pressure. This pipe 8 is bent, as at 8', 85 at the top of the tube 4, and thence extends upward, on the arc of a circle, conforming to the walls of the bowl 5, and lying between said walls, and, at the top of the bowl, is bent so as to present a curved terminal 8", 90 lying in a horizontal plane between the walls of the bowl, and being provided with nozzles 9 projecting through the inner wall 5' of the bowl 5. The pipe 8 is conveniently provided with a valve 10, whereby to adjust 95 the amount or volume of water passing to the bowl 5, or entirely to cut off passage of water thereto.

Connecting the reservoir 2 and the water-supply pipe 8 is a branch 11, in which is a 100 valve 12. By opening this valve, water from the supply-pipe 8 is admitted to the reservoir 2, until the water stands at the desired depth therein, whereupon the valve is closed.

For the purpose of emptying the reservoir 2 of the water therein, a second branch 13 connects the reservoir and the waste-pipe 7, and in this branch is a valve 14, by opening which the water may be drained off 110

from the reservoir, and a fresh supply of clean water admitted thereto.

Within the reservoir 2 are removable wire-mesh baskets 15, 15, each basket being provided with a curved wall 15' conforming in shape to the curvature of the reservoir 2, and with straight walls 15^a, 15^a united by a curved portion 15^b, semi-circular in horizontal cross section. The baskets are disposed, as clearly shown in Fig. 1, with the two curved walls 15', 15' bearing the inner curved surface of the reservoir 2, and with the members of each pair of vertical, flat walls 15^a, 15^a bearing against each other, and with the curved portions 15^b, 15^b encircling the tube 4. The baskets are provided, desirably, with handles 15^c, 15^c, whereby they may be easily removed.

While, for the purpose of the patent-statutes I have described with great particularity one form of embodiment of my invention, it will be understood that the invention is susceptible of modification without necessarily sacrificing any of its advantages, and that all changes from the concrete exemplification herein disclosed come within the scope and purview of the invention, provided they fall within the terms of the appended claims.

My device may be made of any material,—for instance, the reservoir 2 and sputum-bowl 5 may be of porcelain, or of metal.

Having thus fully described my invention, the many advantages thereof will be apparent, especially to those skilled in the art to which it pertains. The device is designed with a view to extreme simplicity, combined with maximum usefulness, and, besides being utilitarian, is ornamental and pleasing to the eye, being graceful in con-

tour, and the exteriors of the reservoir 2 and the bowl 5 being, if desired, painted artistically with any fanciful and ornamental design, or with a harmonious blending of colors.

Having thus fully described my invention, what I claim as new and desire to secure by Letters-Patent of the United States is:

1. In a smoker's utility device, the combination, with twin, open-top receptacles arranged in vertical alinement, of a hollow column connecting said receptacles, liquid supply- and discharge-pipes, respectively, within said column and communicating with said receptacles, and twin, wire-mesh baskets disposed in one of said receptacles, each basket having a wall conforming to and bearing against the inner surface of the wall of said receptacle, and also having a wall shaped in conformity to and bearing against said column.

2. In a smoker's utility device, the combination, with twin, open-top receptacles arranged in vertical alinement, of a hollow column connecting said receptacles, liquid supply- and discharge-pipes, respectively, within said column and communicating with said receptacles, and twin, wire-mesh baskets disposed in one of said receptacles, each basket having a wall conforming to and bearing against the inner surface of the wall of said receptacle, a wall shaped in conformity to and bearing against said column, and straight walls, the straight walls of one basket bearing against the straight walls of the other basket.

In testimony whereof I affix my signature.

BENJAMIN F. KORTEN.
